UNITED STATES PATENT OFFICE.

WILLIAM ALFRED MURRAY, OF BALTIMORE, MARYLAND.

LOCK.

1,256,721.

Specification of Letters Patent. Patented Feb. 19, 1918.

Application filed December 21, 1916. Serial No. 138,173.

To all whom it may concern:

Be it known that I, WILLIAM ALFRED MURRAY, a citizen of the United States, residing at Baltimore city, in the State of Maryland, have invented certain new and useful Improvements in Locks, of which the following is a specification.

This invention relates to improvements in locks and more particularly to a system of locks wherein two keys are necessary to the operation of each lock and the turning of one key to effect an operation of the bolt will at the same operation effectually lock said turning key in place to prevent its removal but will cause the other key to be turned to a position where it can be withdrawn, this latter or withdrawn key, then serving as the operating key for another lock in the series of locks to be successively operated.

While there are a number of systems in which the invention is designed to be used, an explanation of one use to which the invention is particularly applicable is deemed sufficient to explain the utility.

In the collection of mail from street boxes, the collector traverses a given route, going successively from one box to another. Under the present system, a single key, carried by the collector will fit and operate the lock on each box. These collections are presumed to be made at stated times and the public has the right to presume that the mail will be collected at substantially the periods stated.

If a collector, for any reason desires to loiter on his route or by loitering has become late in traversing his route, there is nothing to prevent him making up for the time lost by making short cuts and omitting to visit some of the boxes on his route; consequently whatever mail has been deposited in those boxes must wait for later collection.

The present invention is designed to insure and require that every box, or every lock employed in a system of locks, be operated in a regular or predetermined order or succession and thereby prevent the omission of any one lock in the series.

In carrying out my invention I have designed a series of locks each of which requires two keys for its operation. One key of a lock will be such as to serve as one of two keys for another lock in the series, while

the other key of the same lock will serve as 55 the second key of some other lock to effect an operation of the latter lock.

To make the example a little more explicit, if there are three locks in a series, which, for the purpose of the example will 60 be termed locks A, B, and C, respectively, one key of lock B, will serve as one of the keys for lock A, while the other key of lock B, will serve as one of the keys for lock C, but the removal of the key from lock B, to 65 be operated in lock C, cannot take place until the key from lock A, has been inserted in lock B, and turned to release said lock B, and at the same time said key from lock A, will itself be locked in said lock B, and thus 70 be prevented from removal. Thus each lock will always have a key locked therein when the other key is removed from said lock, so that to operate three locks there must be 75 four keys employed.

To therefore carry out the inventive idea involved no lock in the system can be skipped, because the key for operating one lock must be withdrawn from the lock next before it in the system.

The invention is illustrated in the accompanying drawings, wherein,—

Figure 1, shows a lock in side view and embodying the invention.

Fig. 2, illustrates the same with the key- 85 inclosing caps swung to the open position.

Fig. 3, shows the interior parts of the lock, with one key locked in place and the other key being inserted,—one side wall of the lock case being removed to show the interior 90 parts.

Fig. 4, illustrates the inside view of the wall that fits over the parts in Fig. 3.

Fig. 5, shows the lock in sectional elevation,—the unlocking key being in place and 95 the parts turned to the unlocked position in which the other key may be withdrawn.

Fig. 6, is a cross-sectional detail through the device in the locked position,—the section being taken on the line 6—6 of Fig. 3. 100

Fig. 7, shows another cross-sectional detail through the device, in the unlocked position—the section being taken on the line 7—7 of Fig. 5.

Fig. 8, illustrates in detail a cross-section 105 on the line 8—8 of Fig. 3.

Fig. 9, another cross-section detail on the line 9—9 of Fig. 3.

Fig. 10, shows a detail in vertical section through the lock,—the section being taken on the line 10—10 of Fig. 3.

Fig. 11, illustrates another vertical section through the lock, which latter section is taken on the line 11—11 of Fig. 3.

Fig. 12, shows in perspective a detail of the oscillating locking pawl to lock one key cylinder against rotation when the other key 10 is withdrawn.

Fig. 13, shows a fragment of the lock case with the recess therein to receive the locking pawl operating devices.

Fig. 14, illustrates the detached operating 15 devices for the locking pawl,—the same being shown in perspective, and

Fig. 15, shows three locks in side view together with the keys for operating the same.

Referring to the drawing the numerals 16 20 and 17, designate the two halves or parts of the lock body which have coacting or registering grooves or recesses in which the movable parts of the lock project or seat, as in a mold.

25 When the two halves of the body are together and considered as united, they will be provided with two spaced-apart and parallel cylindrical chambers 18 and 19, respectively, with a cylindrical enlargement 20 and 21, at 30 their respective inner ends and with a cross-wise passage 22, at said inner end which connects said enlargements. Each cylindrical chamber 18 and 19, has a plurality of circular grooves, in the present instance designated 35 23 and 24, in the one and 25 and 26 in the other chamber, as best shown in the half body 16, in Fig. 4, of the drawing.

A cylinder or barrel 27, conforms in shape to and snugly fits the chamber 18, while 40 another cylinder or barrel 28, accurately fits in the chamber 19. The cylinder 27, is provided with circumferential rings 29 and 30, which fit into the circular grooves 23 and 24 of the body, while the cylinder 45 28, carries two rings 31 and 32, which fit into the circular grooves 25 and 26, respectively.

These two cylinders or barrels have enlarged heads 33 and 34, respectively at their 50 inner ends which fit the enlargements 20 and 21, and said cylinders, under certain conditions, are free to rotate in said body-halves, as will presently be more fully explained.

The heads 33 and 34, of said cylinders or 55 barrels 27 and 28, are connected by two link-bars 35,—each link bar having an end pivotally connected to a head, eccentrically, so that when one cylinder or barrel is given a partial rotation, a like movement will be imparted through the link-bars to the other cylinder or barrel.

Each cylinder or barrel is provided with a longitudinal key-slot 36, which extends from the outer end to the head at the inner end,— 60 said key-slots opening all the way through

the cylinders and crossing the rings 29 and 30, in the one barrel and the rings 31 and 32 in the other barrel or cylinder, as clearly seen in Fig. 3.

Each cylinder or barrel also has a short 70 longitudinal locking-slot 37, which extends therethrough and in a direction at right angles to the key slot, as shown best in Figs. 5 and 8, of the drawing. It will be noted that the cylinders or barrels are so positioned in 75 the body, that the key-slot 36, of one and the locking-slot 37, of the other, will face each other when the parts are in the locked position as in Figs. 3 and 8, and that when the parts are turned to the unlocked position, as in Fig. 5, the locking-slot 37, of the one will be opposite to or face the key-slot 36, of the other.

Between the two cylinders or barrels 27, and 28, each half of the body part 16 and 17, 80 has a recess 38, shown in section in Figs. 8, and 10 and in face view in Figs. 4 and 13. Each recess has a circular portion 39, with a segmental slot 40, therein, and a circular plate 41, having a stop lug 42, as shown in 85 Fig. 14, is seated in each recess. Each circular plate 41, is provided with a hub-like projection 43, at one side and from said hub there extends tangentially a lug 44. A spring 45, is wound into a plurality of coils 90 with one end attached to the lug and hub, and the other end of said spring extends into the upper portion of the recess 38, where it is secured by a screw 46. By means of the spring and segmental slot, each plate 41, is 100 permitted a limited rotating movement, the leg 42, and the slot 40, serving to limit this movement.

It will thus be understood that each body part of half of the lock carries one of the 105 hubbed plates 41, and that the hubs of said plates project toward, but are spaced slightly from each other, as shown in Figs. 8, and 10, of the drawings.

Between the two plates 41, and interposed 110 in the space between the ends of the hubs 43, thereof, is a locking pawl 47, which is shown in perspective detail in Fig. 12, of the drawing. This pawl has a pivot pin 48, rigid therewith and extending from opposite 115 sides thereof and one end of this pin enters the hub at one side of the pawl and the other end of said pin enters the hub at the other side of said pawl so that the pawl is mounted to rock in the two hubs and between the 120 latter. The pawl also has two locking arms 49, and 50,—the arm 49, extending toward the cylinder or barrel 27, and the arm 50, projecting toward the cylinder or barrel 28, as clearly shown in Figs. 3 and 8, of the 125 drawings. It will also be noted that the opposite faces of the locking pawl carry segmental flanges 51, which flanges project or extend about the hubs 43, and within the circular space formed by the coils of the 130

spring 45, as shown in Fig. 10, of the drawing.

By reference to Figs. 3 and 8, of the drawings, it will be noted that the arm 49, of the locking pawl projects into the key-slot 36, of barrel or cylinder 27, while arm 50, of said pawl projects into the locking-slot 37, of the barrel or cylinder 28. When in this position neither cylinder can be turned, because the locking pawl arms by projecting in said slots prevents rotation, and the key 52, will be locked in place and cannot be withdrawn.

By referring to Fig. 3, it will be seen that a key 53, is partly inserted in the cylinder or barrel 27, and that the arm 49, of the locking pawl projects in the key slot 36, in the path of the inner end of the key, so that as said key is pushed into the slot, its inner end will engage said arm 49, and swing the pawl from a horizontal to an inclined position, thereby withdrawing arm 49, from key-slot 36, of barrel 27, and also withdrawing arm 50, from the locking-slot 37, of the barrel 28, as clearly shown in Fig. 5, of the drawing, thus releasing both barrels and permitting key 53, to be rotated so as to turn both barrels to the position shown in said Fig. 5. After turning the barrels to the position shown in Fig. 5, the key 52, may be withdrawn,—the pawl, simply yielding to permit the withdrawal of the said key, but as soon as this key 52, has been withdrawn the pawl will spring back to a cross-wise position and its arm 49, will then swing into the locking slot 36, of the barrel 28, thereby again locking the barrels against rotation, and at the same time locking key 53, in place so it cannot be removed.

It will thus be understood that when one key is inserted in a barrel,—the other barrel already having a key locked therein, the last inserted key will serve to rotate both barrels and unlock the key previously locked therein, but during this operation the key last inserted and by which the barrels were turned will itself be locked against withdrawal, so that one key always remains in the lock.

It is also to be understood that of the two keys necessary to the operation of a lock, one will also fit one barrel of another lock (in a series of locks) and the other key will fit one barrel of some other lock, but the same two keys will not fit both barrels of any but the one lock. By this means the key, say 52, of the one lock is withdrawn after the lock has been actuated by the key 53, and the withdrawn key 52, will then be taken to another lock and serve as one of two keys for operating said other lock.

It is believed to be clear that when one barrel or cylinder 27, or 28, is turned, both will be turned because of the link bars 35.

This partial rotation is utilized to retract

the locking bolt and release the spring-actuated shackle with which the present form of lock is provided, as will now be described.

The top of the lock-body above the barrels or cylinders is provided with a cross-wise recess 54, and one end of this recess communicates with the cylindrical enlargement 21, in which the enlarged head 31, is provided with a cam 55, which extends above the top of the head, and said cam is integral with the head and turns with the latter.

This cam, as shown best in Figs. 6 and 7, has two recess portions 56 and 57, respectively and an intermediate raised or rounded portion 58.

The locking bolt 59, is located and has longitudinal movement in the recess 54, and the inner end of this bolt is provided with a pin 60, that enters a recessed head 61, so that a coiled spring 62, may surround the pin and be retained in the recess of said head to constantly press the locking bolt toward the locked position.

The lock shown has the form of a padlock in that it has a shackle 63, which is pivoted to one of the retaining pins or rivets 64, and its free end is provided with a slot 65, into which the end of the locking bolt enters. The free end of the shackle also has a bead 66, which enters a concave recess 67, in a spring actuated ejector head 68, so that when the locking bolt is withdrawn from the slot 65, the head 68, will push the free end of the shackle out automatically and free the latter,—the head 68, moving outwardly in this operation as shown in Fig. 5, and taking position in front of the locking bolt end to hold the latter retracted until the shackle-end is again pressed into engagement with the head to lock it.

The locking bolt 59, is provided on its under side with a pivoted tongue 69, whose free end is engaged and operated by the cam 55,—the two positions of the tongue being shown respectively in Figs. 6 and 7, of the drawing.

For protection to the keys against the weather, I preferably provide a cap or cover 70, which is hinged at the lower corner of the lock by a retaining rivet 71, and the free end of this cap is provided with catch lugs 72, which are engaged by a spring-pressed latch 73, that is pivoted to another retaining rivet 74.

The cap or cover 70, has a narrow slot 75, which receives the heads of the keys and said slot extends in a direction that will only allow the locked key to pass therein,—so that the cap cannot be closed until the unlocked key is removed from the lock, and all danger of possibly leaving the wrong key in the lock is avoided.

While in the present instance the inven-

tion is illustrated in a lock having the form of a pad lock, it is to be understood that it is as readily adapted in locks of other forms.

5 Having described my invention what I claim and desire to secure by United States Letters Patent is,—

1. In a lock the combination with a bolt, of two key-receiving barrels mounted to 10 move in the lock; connections between the barrels to move them simultaneously; means operated by the barrels for actuating the bolt; two keys, and means for locking a key in one barrel and releasing the other key 15 in its barrel when the barrels are operated to actuate the bolt.

2. In a lock the combination with a bolt, of two key-receiving barrels mounted to 20 move in the lock; connections between the barrels to move them simultaneously; means operated by the barrels for actuating the bolt; two keys, and means for locking the barrels against rotation when one key is removed from its key-receiving barrel.

25 3. In a lock the combination with a bolt, of two key-receiving barrels rotatably mounted in the lock; means connecting the two barrels to rotate them simultaneously; two keys; means operated by the barrels for actuating the bolt; means for normally locking the barrels against rotation with a key locked in one barrel and means actuated by the other key for releasing said locking means to allow the barrels to turn.

35 4. In a lock the combination with a bolt, of two key-receiving barrels rotatably mounted in the lock and each barrel having a key slot and a locking slot; two keys; means operated by the barrels for actuating 40 the bolt and means for engaging a key slot of one barrel and a locking slot of the other barrel to prevent rotation of said barrels.

45 5. In a lock the combination with a bolt, of two key-receiving barrels rotatable in the lock and each barrel having a key slot and a locking slot; two keys; means operated by the barrels for actuating the bolt and a locking pawl pivotally mounted between the two barrels and having one end normally engaged in the key slot of one barrel and the other end projecting into the locking slot of the other barrel.

6. In a lock the combination with a bolt, of two key-receiving barrels rotatable in the lock and each barrel having a key slot and a locking slot; two keys; cam means operated by one of said barrels and a pivoted tongue operating between said cam and the locking bolt.

7. In a lock the combination with a bolt, 60 of two key-receiving barrels side-by-side; connections between the barrels for rotating them simultaneously; two keys; means for releasing one key and locking the other against withdrawal when the barrels are rotated and a movable cap for covering the ends of both barrels.

8. In a lock the combination with a bolt, of two key-receiving barrels side-by-side; 70 connections between the barrels for simultaneously rotating the same; two keys; means for locking one key against removal when the barrels are rotated and a cap pivotally sustained adjacent to the ends of the two barrels and having a recess to receive 75 the exposed end of the locked key and to cover the end of the barrel from which the key is removed.

9. In a lock the combination with a lock-body, of a shackle pivoted at one end of said body; a bolt for engaging said shackle; two key-receiving barrels side-by-side in said body; connections between the barrels for rotating them simultaneously; means operated by the rotation of the barrels for actuating 85 the bolt and means for retaining a key in one barrel and releasing a key in the other barrel when the barrels are rotated.

10. In a lock the combination with a lock-body, of a shackle pivoted at one end of 90 said body; two key-receiving barrels side-by-side in the body; connections between the barrels for rotating them simultaneously; two keys; a cap pivoted at the other end of the lock-body and movable over the ends 95 of both barrels and means between the barrels for locking one key in place when the barrels are rotated.

In testimony whereof I affix my signature in the presence of two witnesses.

WILLIAM ALFRED MURRAY.
